2 SHEETS—SHEET 1.

UNITED STATES PATENT OFFICE.

HENRY L. HASKELL, OF LUDINGTON, MICHIGAN, ASSIGNOR TO HASKELITE MANUFACTURING CORPORATION, OF GRAND RAPIDS, MICHIGAN, A CORPORATION OF MICHIGAN.

BOAT.

1,263,410.

Specification of Letters Patent. Patented Apr. 23, 1918.

Application filed November 27, 1916. Serial No. 133,623.

To all whom it may concern:

Be it known that I, HENRY L. HASKELL, a citizen of the United States, residing at Ludington, county of Mason, and State of Michigan, have invented certain new and useful Improvements in Boats, of which the following is a specification.

This invention relates to improvements in boats.

10 The main objects of this invention are:

First, to provide an improved sectional boat.

Second, to provide an improved sectional boat in which the walls are formed of wood veneer, the structure being light in weight and easily portable and at the same time very strong and durable.

Third, to provide an improved sectional boat in which the sections are easily and 20 quickly assembled or knocked down or separated and one which when set up is very secure and the boat as a whole rigid and secure.

Further objects, and objects relating to details and economies of construction and operation will definitely appear from the detailed description to follow.

I accomplish the objects of my invention by the devices and means described in the 30 following specification. The invention is clearly defined and pointed out in the claims.

A structure constituting a preferred embodiment of my invention is illustrated in the accompanying drawing forming a part 35 of this specification, in which:

Figure I is a detail plan view of a boat embodying the features of my invention, the parts being largely shown in conventional form.

40 Fig. II is a detail side elevation of the structure shown in Fig. I.

Fig. III is a transverse section on a line corresponding to line 3—3 of Figs. I and II.

Fig. IV is a transverse section on a line 45 corresponding to line 4—4 of Figs. I and II.

Fig. V is an enlarged detail longitudinal section on a line corresponding to line 5—5 of Figs. I and III showing structural details of the sections and of the manner of 50 joining the same.

Fig. VI is an enlarged detail vertical section corresponding with that of Fig. V showing the clamping member for the section end walls or bulkheads.

Fig. VII is a detail section on a line corresponding to line 7—7 of Fig. II showing structural details of the walls and manner of securing the ribs thereto. 55

Fig. VIII is an enlarged detail vertical section on a line corresponding to line 8—8 of Fig. V showing details of the coupling means for the sections. 60

Fig. IX is a detail vertical section on a line corresponding to line 9—9 of Fig. IV showing further details of the coupling 65 means for the sections.

Fig. X is a detail vertical section on a line corresponding to line 10—10 of Fig. IV, showing still further details of the section coupling members. 70

Fig. XI is a perspective view of one of the slotted coupling members.

Fig. XII is a detail horizontal section on a line corresponding to line 12—12 of Fig. III showing still further details of the section 75 coupling means.

In the drawing similar reference characters refer to similar parts throughout the several views, and the sectional views are taken looking in the direction of the little 80 arrows at the ends of the section lines.

Referring to the drawing, the walls 1 of the boat are formed of wood veneer, the structure shown being made up of three plies which are secured together by a waterproof 85 glue or cement. I have only illustrated three sections of a boat designated generally by the numerals 2, 3 and 4. These sections are provided with gun-wale sections 5 which are grooved at 6 to receive the upper edges of 90 the walls. At the end of each section is an angle iron rib 7 secured to the side walls by copper rivets 8, a suitable gasket 9 being arranged between the ribs and the walls. The sections are provided at their meeting ends 95 with end cross walls or bulkheads 10, the end cross walls being secured to the ribs by rivets 11, the ribs and cross walls being arranged so that the outer faces of the cross walls are flush with the edges of the outer 100 walls of the sections. These end walls are also preferably formed of wood veneer, made up of suitable layers or plies and they serve to stiffen and brace the side walls although their main function is that of bulkheads and 105 connecting means for the sections.

At each side and above the cross walls at one end of the intermediate sections are

dowel plates 12 having holes therein adapted to receive the removable dowels 13 carried by the abutting section. See Figs. III, IV, IX. The sections are coupled at their bottoms by couplings consisting of clips 14 having raised bosses 14' pressed therefrom to form recesses between the clips and the ribs 7, the bosses having slots 15 therein. On the abutting sections are headed coupling members 16 adapted to be engaged with these slots, the heads of the coupling members sliding into the recesses between the ribs and the clips. The bottom veneer adjacent said clip is cut away as indicated at 15' to admit the head of the headed member to the recess between the clip and the rib. The sections are further secured by cross members 17 which, in the structure illustrated, are formed of wood veneer and adapted as seats for the boat. The ends of these cross members are notched at 18 to embrace the ribs and are provided with clamping members 19 on their under sides having longitudinal grooves 20 therein engaging the upper edges of the cross walls and clamping them together, preferably from end to end. I preferably provide a packing strip 21 at the upper edges of the cross walls. The cross member is preferably a wedging fit so that when it is forced into place the sections are securely locked and retained together, the coupling members at the bottom preventing the separating at the bottom while the cross member holds them together at the top and the dowels supporting them against lateral movement.

To assist in clamping and retaining the cross member, I provide pivoted cam members 22 at the ends of the cross member and coacting keepers 23 on the ribs, (see Fig. VIII) the fasteners shown being such as are quite well known as sash fasteners.

With this arrangement of parts, the sections can be quickly joined or assembled without the aid of tools and may be as quickly disassembled or knocked down. By forming the walls of wood veneer, the sections are comparatively light so that they are readily portable and at the same time possess great strength particularly when reinforced and supported by the cross walls and securing means as I have illustrated and described. The sections may be constructed so as to be nested when disassembled. I have not shown them nested as it is merely a matter of proper proportioning to permit their being nested.

I have illustrated and described my improvements in the form in which I have embodied the same in practice. I have not attempted to illustrate or describe various modifications which I contemplate as I believe the disclosure made will enable those skilled in the art to which my invention re-

lates to embody or adapt the same as conditions or taste may dictate. I desire, however, to claim my improvements specifically in the form illustrated as well as broadly within the scope of the appended claims. 70

Having thus described my invention, what I claim as new and desire to secure by Letters Patent, is:

1. In a boat, the combination of body sections comprising outer walls provided with end ribs at their meeting ends and with end cross walls, the upper edges of the cross walls being below the top of the side walls, dowel plates on one section and coacting dowels on the other disposed on the end ribs above said cross walls, couplings comprising recessed clips having slots therein secured at the bottom of one section, coacting headed coupling members secured to the adjacent section, the heads of said members being adapted to be slid into the recessed portions of the clips, the bodies of the coupling members extending through said slots, a cross member notched at its ends to engage adjacent ribs and having a longitudinal clamping member on its under side grooved to engage the upper edges of the cross walls, and clamping cams for said cross member. 85

2. In a boat, the combination of body sections comprising outer walls provided with end ribs at their meeting ends and with end cross walls, the upper edges of the cross walls being below the top of the side walls, dowel plates on one section and coacting dowels on the other disposed on the end ribs above said cross walls, couplings comprising recessed clips having slots therein secured at the bottom of one section, and coacting headed coupling members secured to the adjacent section, the heads of said members being adapted to be slid into the recessed portions of the clips, the bodies of said members extending through said slots. 100

3. In a boat, the combination of body sections provided with end cross walls, couplings comprising recessed clips having slots therein secured at the bottom of one section, coacting headed coupling members secured to the adjacent section, the heads of said members being adapted to be slid into the recessed portions of the clips, the bodies of said members extending through said slots, connecting dowels at the sides of said sections, and means for detachably connecting the said sections toward the top thereof. 115

4. In a boat, the combination of body sections comprising outer walls provided with end ribs at their meeting ends and with end cross walls, connecting dowels at the sides of the sections, couplings comprising recessed clips having slots therein secured at the bottom of one section, coacting headed 120

coupling members secured to the adjacent section, the heads of said members being adapted to be slid into the recessed portions of the clips, the bodies of said members extending through said slots, and means for detachably connecting the upper ends of the ribs and the upper edges of said cross walls.

5. In a boat, the combination of the body sections comprising outer walls provided with end ribs at their meeting ends and with end cross walls, couplings comprising recessed clips having slots therein secured at the bottom of one section, coacting headed coupling members secured to the adjacent section, the heads of said members being adapted to be slid into the recessed portions of the clips, the bodies of said members extending through said slots, and means for detachably connecting the upper ends of the ribs and the upper edges of said cross walls.

6. In a boat, the combination of the body sections comprising outer walls provided with end ribs at their meeting ends and with end cross walls, connecting dowels at the sides of the sections, couplings comprising slotted members secured at the bottom of one section and coacting headed coupling members secured to the adjacent section, and means for detachably connecting the upper ends of the ribs and the upper edges of said cross walls.

7. In a boat, the combination of the body sections comprising outer walls provided with end ribs at their meeting ends and with end cross walls, couplings comprising slotted members secured at the bottom of one section and coacting headed coupling members secured to the adjacent section, and means for detachably connecting the upper ends of the ribs and independent means for detachably connecting the upper edges of said cross walls.

8. In a boat the combination of the body sections provided with end cross walls, connecting dowels at the sides of the sections, couplings comprising slotted members secured at the bottom of one section, coacting headed coupling members secured to the adjacent section, and means for detachably connecting the tops of the sections.

9. In a boat, the combination of body sections provided with end cross walls, slotted coupling members disposed at the bottom of one section, coacting headed coupling members on the adjacent section, a cross member adapted as a seat and to engage the upper edges of the cross walls, and fasteners for said cross member consisting of cams pivotally mounted on said cross member and coacting keepers on said ribs.

10. In a boat, the combination of body sections provided with end cross walls, slotted coupling members disposed at the bottom of one section, coacting slotted head-

ed coupling members on the adjacent section, a cross member adapted as a seat and having a longitudinal clamping member on its under side grooved to engage the upper edges of the cross walls, and a packing strip disposed at the upper edges of the cross walls.

11. In a boat, the combination of body sections provided with end cross walls, slotted coupling members disposed at the bottom of one section, coacting headed coupling members on the adjacent section, and a cross member adapted as a seat and having a longitudinal clamping member on its under side grooved to engage the upper edges of the cross walls.

12. In a boat the combination of complementary sections comprising outer walls provided with end ribs at their meeting ends and with end cross walls, connecting dowels at the sides of the sections, slotted coupling members disposed at the bottom of one section, coacting headed coupling members on the adjacent section, a cross member adapted to engage adjacent ribs and the upper edges of the cross walls, and a packing strip disposed at the upper edges of the cross walls.

13. In a boat, the combination of body sections comprising outer walls provided with end cross walls, and means for detachably connecting said sections comprising a cross member adapted as a seat and having a longitudinal clamping member on its under side due to engage the upper edges of the cross walls, and a packing strip disposed at the upper edges of the cross walls.

14. In a boat, the combination of body sections comprising outer walls provided with end cross walls, and means for detachably connecting said sections comprising a cross member adapted as a seat and having longitudinal clamping member on its under side due to engage the upper edges of the cross walls.

15. In a boat, the combination of body sections comprising outer walls provided with end cross walls, connecting dowels at the sides of the sections, slotted coupling members disposed at the bottom of one section, coacting headed coupling members on the adjacent section, and means for connecting the sections toward the top thereof to prevent their longitudinal separation.

16. In a boat, the combination of body sections comprising outer walls provided with end cross walls, slotted coupling members disposed at the bottom of one section, coacting headed coupling members on the adjacent section, and means for connecting the sections toward the top thereof to prevent their longitudinal separation.

17. In a boat, the combination of body sections comprising outer walls provided with end ribs at their meeting ends and with end

cross walls, and means for detachably connecting said sections comprising a member adapted to engage said ribs and cross walls.

18. In a boat, the combination of body sections comprising outer walls provided with end ribs at their meeting ends and with end cross walls, and means for connecting said sections comprising a cross member adapted as a seat and notched at its ends to engage 10 said end ribs and having a longitudinal clamping member on its under sides due to engage the upper edges of the cross walls, a packing strip disposed at the upper edges of the cross walls, and a cam means for removably securing said seat.

19. In a boat, the combination of body sections comprising outer walls provided with end ribs at their meeting ends and with end cross walls, and means for connecting said 20 sections comprising a cross member adapted as a seat and notched at its ends to engage said end ribs and having a longitudinal clamping member on its under sides due to engage the upper edges of the cross walls.

25 20. In a boat, the combination of complementary sections comprising outer walls formed of plies of wood veneer cemented or glued together throughout by waterproof glue and provided with end ribs at their 30 meeting edges, the outer walls being secured to said ribs by rivets, end cross walls formed of wood veneer for the meeting end of said sections, the end edges of the outer walls being flush to the outer surface of the ends of the cross walls, the end walls being riveted to 35 said end ribs, and means for detachably to said end ribs, and means for detachably

connecting said sections comprising a cross member formed of wood veneer and adapted as a seat and slotted at its ends to engage said ribs and having a longitudinally 40 grooved clamping member on its under side engaging the upper edges of said cross walls.

21. In a boat, the combination of complementary sections comprising outer walls formed of plies of wood veneer cemented or 45 glued together throughout by waterproof glue and provided with end ribs at their meeting edges, the outer walls being secured to said ribs by rivets, end cross walls formed of wood veneer for the meeting end of said 50 sections, each edge of the outer walls being flush to the outer surface of the ends of the cross walls, the end walls being riveted to said end ribs, and means for detachably connecting said sections.

22. In a boat, the combination of complementary sections comprising outer walls formed of plies of wood veneer cemented or glued together throughout by waterproof glue and provided with end ribs at their 60 meeting edges, end cross walls formed of wood veneer secured to said end ribs, and means for detachably connecting said sections comprising a cross member formed of wood veneer and adapted as a seat and slotted at its ends to engage said ribs and having a longitudinally 65 grooved clamping member on its under side engaging the upper edges of said cross walls.

In witness whereof, I have hereunto set 70 my hand and seal.

HENRY L. HASKELL. [L.S.]
